UNITED STATES PATENT OFFICE.

EMIL J. LEHR, OF ST. LOUIS, MISSOURI.

DESIGN FOR AN ANTIGLARE DEVICE FOR HEADLIGHTS.

Application filed June 22, 1925. Serial No. 13,856. Term of patent 14 years.

To all whom it may concern:

Be it known that I, EMIL J. LEHR, a citizen of the United States, residing in the city of St. Louis and State of Missouri, have invented a new, original, and ornamental Design for an Antiglare Device for Headlights, of which the following is a specification, reference being had to the accompanying drawing, forming part thereof.

Fig. 1 is a face view of my device.

Fig. 2 is a sectional view along the line 2—2 of Fig. 1.

I claim:

The ornamental design for an antiglare device for headlights, as shown.

EMIL J. LEHR.
